UNITED STATES PATENT OFFICE.

ALBERTUS A. LONGMAN, OF DAYTON, OHIO, ASSIGNOR TO THOMAS J. FARRELL, OF SAME PLACE, AND WILLIAM BOTT AND JOSEPH BOTT, OF COLUMBUS, OHIO.

DESIGN FOR A GAME-TABLE.

SPECIFICATION forming part of Design No. 30,380, dated March 21, 1899.

Application filed January 28, 1899. Serial No. 703,754. Term of patent 14 years.

To all whom it may concern:

Be it known that I, ALBERTUS A. LONGMAN, a citizen of the United States, residing at Dayton, in the county of Montgomery and State of Ohio, have invented and produced a new and original Design for a Game-Table, of which the following is a specification, reference being had to the accompanying drawings, forming part thereof, and in which like characters refer to correspondingly-formed parts.

My invention relates to a design for a game-table for use either in public or private houses, which game is played with a cue and two balls.

15 Figure 1 is a perspective view of a game-table embodying my new and useful design. Fig. 2 is a plan view thereof. Fig. 3 is a side elevation thereof, and Fig. 4 is a rear end view thereof, these four views being deemed essential to fully illustrate my new and useful design.

The top of the table is on an incline, low at its front end and high at its rear end, and the table-top is inclosed by a U-shaped vertical 25 flange on its edges, formed of portions A, B, and C, the portion C thereof at the rear end of the table being semicircular. Parallel with the portions A B of said U-shaped flange are vertical flanges II and I, pointed at their rear 30 ends J, near the curved portion C of said U-shaped flange, thus forming an opening into the inclosed surface of said table-top for the grooves formed between said flanges II and I and their respective portions A and B of the 35 U-shaped flange. Between the front ends of the flanges II and I and upon the front of the table-top is a vertical flange K, on whose rear edge is formed a series of concaved recesses K'. The front ends of the grooves on the long 40 sides of the table-top are closed by rectangular portions E and F, each having a circular groove G formed in its top surface and opening into its rear end.

On the top surface of the table, inclosed 45 within the flanges on its edges, are a series of circular characters K³, K⁴, K⁵, K⁶, and K⁷, ar-

ranged substantially in the form of a base-ball diamond.

Projecting vertically from that portion of the top surface of the table between the 50 grooves on its long sides and near the front edges of the characters K⁴ and K⁷ are a series of circular projections L, arranged at intervals.

Near each corner the table has downward 55 projections or legs M, between the tops of which extend molded portions N. From the center of the molded portion N on the front end of said table projects a rectangular portion O, extending parallel with the table-top 60 and beyond the front edge thereof, and in the top of said portion O is a recess P.

Upon the rear edge of said table and projecting therefrom is a bracket D, whose edges are formed with curves or scrolls.

65 The essential feature of my design for a game-table consists of a game-table provided with an inclined top, having a U-shaped flange near its side and rear edges, a flange near its front edge, having recesses in its inner surface, a groove on the side of said table-top opening at its rear end onto the table-top, a series of characters on said table-top arranged in substantially the form of a base-ball diamond, a series of circular projections projecting at intervals from a portion of the surface of said table-top, a bracket projecting from one edge of said table, an inclined portion projecting from one edge of said table below the table-top and extending beyond the same, 70 and a recess in the top of said inclined portion.

75 What I claim is—

The design for a game-table, substantially 80 as shown and described.

85 In witness whereof I have hereunto set my hand this 18th day of January, 1899.

ALBERTUS A. LONGMAN.

Witnesses:

ISAAC G. KENNEDY,
IRA C. KOEINE.
